UNITED STATES PATENT OFFICE

VIRGIL E. GRAHAM, OF HERSHEY, NEBRASKA

FRAME FOR CALENDARS AND THE LIKE

Application filed October 10, 1929. Serial No. 398,728.

The invention relates to ornamental frames for calendars and other articles and has for its object the provision of a frame provided with a pocket on its rear side having the mouth of the pocket at the lower end of the frame, the pocket being provided with an opening in the upper portion thereof to expose a hanging device secured to the calendar or other article, so that the calendar and frame may be hung by the hanging device secured to the calendar and the calendar will support the frame.

The invention will be described in detail hereinafter and will be found illustrated in the accompanying drawings in which

Figure 1 is a front view in elevation of the improved frame showing the calendar displayed therein,

Figure 2 is a rear view,
Figure 3 is a horizontal sectional view on a plane indicated by the line 3—3 of Figure 1.

Figure 4 is a vertical sectional view on a plane indicated by the line 4—4 of Figure 1,
and

Figure 5 is a fragmentary sectional view on a plane indicated by the line 5—5 of Figure 1.

In the drawings similar reference characters are used to designate corresponding parts in all of the views.

In the drawings the frame member is designated 1 and is provided with an opening 2 for display of a calendar or other article 3. Secured to the rear side of the frame 1 is a sheet of material 4, said sheet of material being secured in any suitable manner as shown at 5 on the upper bar 6 of the frame and secured as shown at 7 to the end bars 8, the lower edge of the material 4 being left unsecured and forming the opening to the pocket 9 to receive a calendar or other article. 10 indicates an opening adjacent to the secured upper edge 5 in the sheet of material 4 to expose a hanger 11 secured to the calendar or other article 3 for convenience in hanging the frame and calendar, or other article. 12 indicates a sheet of transparent material that may be secured on the rear side

of the frame 1, or if desired the transparent panel 12 may be omitted.

In use it will be apparent that the frame may be used for advertising purposes and when used for hanging calendars may be used from year to year by removing an obsolete calendar at the end of the year and replacing it with a calendar for the current year, it being apparent also that the calendar may be readily removed for the purpose of tearing off the sheet for the expired month to expose the sheet for the current month.

What is claimed is:—

1. A frame for calendars and the like, comprising a frame member having a sight opening therein, a sheet of material secured to the back of said member at some of the edges thereof and providing, with the frame member, a pocket to hold an article for display through said opening, and the sheet of material being provided with an aperture adapted to expose a hanging means secured to said article.

2. A frame for calendars and the like, comprising a frame member having a sight opening therein, a sheet of material secured at its edges on the top and sides of the back of said frame member and forming a pocket for display of an article through said sight opening, said sheet of material being provided with an aperture adjacent to the secured top edge thereof to expose a hanging means secured to said article.

In testimony whereof I affix my signature.

VIRGIL E. GRAHAM.
